UNITED STATES PATENT OFFICE.

ROY L. WADLEIGH, OF LUVERNE, IOWA.

STAPLE-PULLING IMPLEMENT.

Application filed April 12, 1922. Serial No. 551,907.

To all whom it may concern:

Be it known that I, ROY L. WADLEIGH, a citizen of the United States, residing at Luverne, in the county of Kossuth and State 5 of Iowa, have invented certain new and useful Improvements in Staple-Pulling Implements, of which the following is a specification.

The present invention relates to a device 10 for pulling out staples from posts and boards, and its main object is to provide an implement of this class which is comparatively light and easy to handle, while the work for which it is intended is performed rapidly without bending or injuring the staples in any manner.

The implement can be handled equally well by right handed and left handed persons and will pull staples from the top or 20 bottom of a post without requiring any resetting or adjustment.

One embodiment of the invention is illustrated in the accompanying drawing, and

Figure 1 is a top plan view of the implement in operation,

Figure 2 is a side elevation looking in the direction of arrow X of Figure 1, and

Figure 3 is a transverse section along line 3—3 of Figure 2.

30 The staple puller consists of a handle 10 which is preferably made of wood and of any suitable length. The forward end of the handle is higher and tapered to a blunt point or heel 11 which stands above the bottom of the implement, as ordinarily held (see Figure 2).

Along the bottom 9 of the handle is rigidly secured by means of bolts 12, a steel or iron head 13 which for this purpose is 40 provided with a thin shank 14. From the corner 15 of the handle, where the taper commences, the head runs outward (see Figure 1) to form a goose-neck 16, which increases gradually in thickness, so as to provide a broad base 17 at the right side of the head. This provides a uniform thickness along the flat surface 18 and from the line 45 19 in Figure 1 the head tapers down forming a bill 21 with a sharp point 20. As best seen in Figure 1, a deep incision or recess is provided between the bill and the goose-neck, at 22, the bill having a straight rear portion 23 along its inner side. The outer face 24 of the bill and of the head is curved 50 providing a rolling surface and it will readily be seen that a good purchase is, in

this manner, furnished for pulling a staple 25, when the point 20 of the bill is inserted in the exposed opening of the staple 25.

The use of the implement is as follows:

Supposing a staple 25 with its loop opening to the side, is situated anywhere up to about four feet from the ground in an upright post 26, the bill point 20 is then inserted into the loop from one side as seen in Figures 1 and 2, with the blunt point or heel 11 uppermost. A blow with a hammer is then applied on the base 17 which, in this case, would be situated to the right of the operator, in order to drive the bill point further 70 into the loop of the staple and slightly loosen the same. The end of the handle is now pushed upwards, when the implement will be made to tilt on the point 11 until the staple is detached. It will be readily seen 75 that as there is no twisting motion, the staple will come out intact without being bent, so that it may be used again when needed.

Supposing the staple is situated more than four feet above the ground, the implement is then inserted with the bill point in the loop of the staple 25, but with the implement held upside down, that is, in reversed position to that seen in Figure 2, namely, 80 with the bill point 20 to the right and the base 17 to the left of the operator. By again delivering a blow with a hammer against the base 17, the bill point 20 is driven further into the opening of the staple 25, thereby loosening it and by finally pulling downward on the end of the handle, the staple 90 25 will be detached from the post.

At times it might not be possible to swing the handle in a vertical plane with a staple 95 situated as shown in Figure 2, and when there is only room for a sidewise motion of the handle. In such a case, the bill point 24 is inserted in a staple as before, but instead of tilting the head around the point 11, a transverse motion of the handle is performed, so that the convex surface 24 at the forward end of the head 13 contacts with the board or post in which the staple is situated, until the latter is again detached 100 from the wood.

It will be evident that the operation of this staple puller is extremely simple and no great exertion is required of the operator to lift the implement or to detach the staples 110 from the wood. As the head and the handle are rigidly connected by means of

bolts to form a unit, no adjustment is required in the use thereof.

The handle of this implement is preferably made of hard wood and the head is made of a good grade of steel, the bill point thereof being tempered.

From practical experience it has been proved that the operator is able to pull out staples much quicker than any man can 10 drive them in, even if they are seated firmly in the material.

The implement may, of course, be used for pulling staples situated in any other position than that described as, for instance, with the 15 shanks of the staples situated in a horizontal or an inclined plane, in a post or board, when the staple puller naturally would be held in a different position to that which has been described, but the action and the 20 result would be the same.

It may also be conceived that it might be

desired to pull staples out of boards in the floor or ceiling of a building, in which case the implement would be held in perpendicular position.

Having thus described the invention, what is claimed as new is:

A staple puller having a handle, a head rigidly and permanently secured on the handle and provided with a bill, said bill having a straight inner edge and an outer edge tapering from the point of the bill and in the length direction thereof terminating in a broad square base at the opposite side of the head, a goose-neck connecting said head with said handle; the forward end of the handle terminating in a heel spaced transversely to the plane of said bill and providing a fulcrum for the same when the handle is rocked transversely to the said plane.

In testimony whereof I affix my signature.

ROY L. WADLEIGH. [L. s.]
